KERF-CUTTING MINING MACHINE

Thomas E. Pray, Chicago, Ill., assignor to Goodman Manufacturing Company, Chicago, Ill., a corporation of Illinois

Application July 12, 1941, Serial No. 402,052

16 Claims. (Cl. 262—29)

This invention relates to improvements in kerf-cutting mining machines, and more particularly to track mounted machines having a plurality of superimposed cutter bars adapted to cut relatively thick bands of coal or dirt from coal seams, and load the material as cutting proceeds.

The principal object of my invention is to provide a machine of the character described, having means for adjusting the cutting height of the cutter bar at varying levels ranging from the mine floor to the roof of the mine.

A machine of the present invention employs many of the features of machines disclosed in my prior Patent No. 2,082,199, issued June 1, 1937, and prior application Serial No. 362,743, filed Oct. 25, 1940, but includes an improved form of cutter head having three cutter bars, together with a novel means for supporting the cutter head for vertical adjustment well in advance of the truck, and with means for conveying the cuttings rearwardly to the truck for final discharge rearwardly of the latter, in all positions of adjustment of said cutter head.

The invention may best be understood by reference to the accompanying drawing, in which

Figure 1 is a plan view of a machine constructed in accordance with my invention;

Figure 2 is a side view of the machine shown in Figure 1;

Figure 3 is an enlarged longitudinal section of the cutter head;

Figure 4 is an enlarged longitudinal section of the rear end of the cutter head including its driving connection and a portion of the cuttings conveyor;

Figure 5 is a detail plan view of the cutter head drawn to a slightly smaller scale than Figures 3 and 4, with a part of the side frame shown in section and with a part of the frame broken away at the front thereof;

Figure 6 is a horizontal section taken on line 6—6 of Figure 3;

Figures 7, 8 and 9 are transverse sections of the cutter bars, taken on lines 7—7, 8—8 and 9—9, respectively, of Figure 5;

Figure 10 is an enlarged fragmentary detail section taken on a longitudinal vertical plane, showing the cutter head supporting members in elevated position;

Figure 11 is a fragmentary detail plan view showing the central and rear part of the machine, with certain parts shown in section;

Figure 12 is a detail side view of the rear end of the machine, with certain parts shown in section;

Figure 13 is a detail section taken on line 13—13 of Figure 11;

Figure 14 is a detail section taken generally on line 14—14 of Figure 11; and

Figure 15 is a detail section of a sliding sheave forming part of the turntable rotating mechanism.

Referring now to details of the embodiment of my invention illustrated in the drawings, the machine generally comprises a wheeled truck 10, herein adapted to travel along mine tracks 11 and having a base frame 12 with a turntable 13 at the front end to which a cutter head 14 is connected by a forwardly extending, vertically swinging, supporting structure, indicated generally at 15.

The wheeled truck 10 and its base frame 12 includes a generally flat deck 12a and depending front wheel supports 16, 16 with track wheels 17, 17 thereon, and similar rear wheel supports 18, 18 with track wheels 19, 19 thereon. The wheel supports on opposite sides of the frame are separated so as to leave a central space for a conveyor 20 extending longitudinally of the base 12 beneath the deck 12a for carrying away the cuttings discharged thereon from the cutting mechanism, as will presently appear.

The turntable 13 comprises an annular base plate 22 having a depending hub portion 23 rotatably mounted in a bearing member 24 on the deck 12a (see Figures 10 and 14). A circular hopper-like opening 25 is formed through the hub 23 communicating with the cuttings conveyor 20 below the deck.

Extending rearwardly from the turntable base plate 22 are two laterally spaced bearing brackets 27 to which are pivotally connected an upright control frame 28 which is arcuate in horizontal section, and has each of its opposite side walls bifurcated at 29, 29. A pair of upper and lower supporting arms 30, 30 and 31, 31 are pivoted on pins 32 and 33 respectively between the bifurcated side wall portions 29, 29, at opposite sides of the control frame 28. The two pairs of supporting arms 30 and 31 extend forwardly in parallel relation to each other along the turntable and thence downwardly at similar angles, where they are pivotally connected to lugs 34, 34 and 35, 35, respectively, at opposite sides of the cutter head 14, adjacent the forward end thereof. Said cutter head has a pair of upright projecting ribs 36, 36 formed adjacent its rear end, having bearing engagement between the inner faces of arms 30 and 31 and assisting in maintaining the respective parts in longitudinal

alignment with each other. The supporting arms 30 and 31 thus provide a parallel link motion in which the cutter head 14 can be moved vertically into varying parallel cutting planes, perpendicular to the control frame 28.

The rear ends of the supporting arms 30 and 31 are guided between a pair of laterally spaced upright guide frames indicated generally at 37, 37 mounted on the front of the turntable 13, and projecting forwardly thereof. Said guide frames each comprise a base member 38, two uprights 39 and 40, and a horizontal brace 41, connecting the upper ends of said uprights 39 and 40.

At the front end of each of the guide frames 37 is a depending bifurcated bracket 43, offset inwardly of the adjacent supporting arms 30 and 31. Hydraulic elevating cylinders 44, 44 have their lower ends pivotally mounted between the arms of said brackets. Each of said cylinders has a piston 45 therein, and a piston rod 46 extending from its upper end, and pivotally connected to a bracket 47 on the inner side of the adjacent upper supporting arm 30, as shown in Figures 10 and 13. The hydraulic cylinders 44 serve to raise and lower the cutter head 14 relative to the turntable 13, and maintain said cutter head in any desired cutting plane.

The cutter head 14 includes a housing 50 having side walls 51, 51 and a bottom 52, which has an elongated centrally disposed upright pedestal 53 adjacent its forward end, to which the rear ends of cutter bars 54, 55 and 56 are connected, as by bolts 57 and 58. The housing 50 also has a second centrally disposed upright pedestal 59 adjacent its rear end, which provides a suitable bearing support for a cutter chain sprocket shaft 60 at the rear of the frame. An intermediate bearing support 61 for a second sprocket shaft 62 is mounted on horizontal webs 65, 65a and 66, 66a between the upper ends of the pedestals 53 and 59. As will presently be described in detail, the rear sprocket shaft 60 has chain sprockets 63 and 64 for the cutter chains of the two lower cutter bars 55 and 56, while the intermediate sprocket shaft 62 has a sprocket 62a for the cutter chain of upper cutter bar 54.

As shown herein, the two lower cutter bars, with their cutter chains, extend to the rear end of the housing 50, but the upper cutter bar with its cutter chain extends only part way to the rear of said housing, terminating at a semi-circular upright wall 67 (see Figure 3).

A circular gear casing 69 having a removable cover plate 70, is formed concentric with the rear sprocket shaft 60, for enclosing bevel gears 71 and 72 which drive said rear sprocket shaft, as will presently appear. The arrangement is such that the side walls 51 and bottom 52 of the housing 50 form in effect channels extending longitudinally along opposite sides of the three cutter bars, and below the gear casing 69. The rear ends of said channels terminate at a cuttings discharge opening 74 at the rear end of the housing 50.

The cutter head also includes means for collecting the cuttings brought back from the kerf by the cutter chains, so that the cuttings will be carried rearwardly along the channel at the advancing side of the cutter bars and through the discharge opening 74 where they will be deposited on a conveyor 75, as will presently be described in detail. The cuttings collecting means shown herein is somewhat similar to that disclosed in a co-pending application Serial No. 362,743, filed 75

by me on Oct. 25, 1940, and consists of an extension chute 76 telescopically mounted in one of the channels beneath and to one side of the lower cutter bar 56 and arranged to be extended forwardly into endwise engagement with the mine wall beneath the kerf, to catch the cuttings as they are brought rearwardly by the cutter chains. As herein shown, said chute is disposed in the left-hand channel, since the cutter chains are

usually driven in a counterclockwise direction. The chute 76 has an extended upright outer wall 77. The front end of the chute is supported by a horizontal plate 78, which extends laterally beneath the cutter bars and is secured by an upper right bolt 79 to a roller frame 80 (see Figure 7). Said roller frame is guided for movement along registering slots 81, 81 formed centrally of the cutter bars, by means of a plurality of vertically disposed rollers 82, 82 and horizontally disposed rollers 83, 83 carried by the roller frame 80.

A horizontally extending shoe 85 is pivotally supported beneath the front end of chute 76 and is arranged to have sliding engagement with the mine wall when the machine is in cutting position.

Means are provided for yieldingly urging the chute in a forward direction and maintaining it in engagement with the mine wall, which comprise a cable 86 connected at one end to an abutment 87 at one side of the chute. (See Figure 5.) Said cable is trained over a sheave 88 near the front of the housing 50 and thence rearwardly where it is connected to an elongated coil spring 89 in a housing 89a mounted along the side of said housing. The spring 89 is normally under tension to maintain the chute in yielding contact with the mine wall at varying degrees of penetration of the cutter bars.

The cutter chains are driven by an electric motor 90, mounted on the turntable 13 and having flexible driving connections with the cutter head so as to permit freedom of vertical adjustment of the latter. In the form shown herein, the motor is pivotally mounted on pins 91, 91 carried by a pair of pedestals 92, 92 at the rear end of the turntable 13 between the rear ends of the parallel arms 30 and 31 so that the motor is free to be tilted on a transverse axis. The motor casing has a forward extension 93 forming in effect a cross head with upright wings 94, 94, each having an elongated slot 95 therein slidably engaged by a block 96 carried on the inner side of the adjacent upper parallel arm 30 (see Figure 10). With this arrangement, the motor 90 is rocked upwardly and downwardly with the parallel arms 30 and 31 so as to accommodate itself to various positions of vertical adjustment of the cutter head 14.

The extension frame 93 has two centrally aligned bearing supports 97, 98 for a drive shaft 99 connected with said motor. A horizontal shaft 100 is journaled in the rear end of the gear casing 69 on the cutter head 14, and is flexibly connected to the drive shaft 99 by two universal joints 101, 102 and a telescopic shaft 103, of the usual construction.

The shaft 100 has a bevel pinion 71 fixed thereon, meshed with a bevel gear 72 keyed on the upper end of the rear cutter chain sprocket shaft 60 (see Figures 3 and 4). Said sprocket shaft is journaled at its upper end in suitable bearings 106, 106 and extends downwardly through a depending bearing support 108. An elongated sleeve 107 is rotatably mounted on said bearings 106, 106 and has an outer sleeve 109 carried

thereon. The two sleeves 107 and 109 are suitably connected to the lower end of the sprocket shaft 60 as by an end plate 110. The cutter chain sprockets 63 and 64 are formed integral with the sleeve 109, for driving the cutter chains 55a and 56a of the two lower cutter bars 55 and 56 respectively.

Between the two sprockets 63 and 64 is mounted a sprocket 113 for a drive chain 114, which leads forwardly to a sprocket 115 keyed on the lower end of sprocket shaft 62. As previously described, the shaft 62 has a cutter chain sprocket 62a keyed on its upper end, for driving the cutter chain 54a of the upper cutter bar 54. The cutter chains of the three juxtaposed cutter bars are arranged as usual to cut a kerf substantially thicker than their respective cutter bars, and in the present instance said cutter bars are disposed so closely to each other that their cutter chains collectively present a substantially unitary side cutting edge for cutting a single kerf, which is substantially the full height of the cutter head 14. The upper limit of the cutting plane of the upper cutter chain 54a is substantially above the gear casing 69 with its drive connection. The two lower cutter bars extend all the way to the rear end of the cutter head frame, beneath the gear casing 69, so as to carry the cuttings from all three cutter bars rearwardly and discharge them upon the conveyer 75 at the rear of said frame.

The auxiliary conveyer 75 consists of a trough-like frame 111, having an endless conveyer chain 116 with transverse flights 116a, 116b thereon, arranged to carry the cuttings along a plate 117. The chains are trained over a pair of sprockets 118, 119 on a sprocket shaft 119 at the front end of the conveyer, and suitable idler sprockets (not shown) at the rear end of said conveyer, as usual.

The sprocket shaft 119 also has bearing at opposite ends in brackets 120, 123 depending from the rear end of housing 50, so as to form a pivotal support for the auxiliary conveyer, permitting vertical swinging movement of the latter when the cutter head is in its various adjusted positions relative to the base frame 12. The conveyer is driven by a chain 121 engaging a sprocket 122 at one end of the sprocket shaft 119, and a sprocket 123 on a stub shaft 124, driven from the shaft 109 through bevel gears 125 and 126 (see Figures 4 and 5).

The conveyer 75 extends rearwardly to span the space between the cutter head and the turntable 13, and the rear end of said conveyer projects over the front edge of said turntable so as to discharge into the hopper 25 in the center of said turntable. A pair of oppositely disposed upright guide blocks 127, 127 are mounted on the front edge of the turntable to maintain the rear end of the conveyer in registering position over the hopper.

The cuttings delivered to the hopper 25 are carried rearwardly of the machine on the conveyer 20. In the form shown in Figure 2, the rear end of conveyer 20 is inclined upwardly at 21a and overhangs the rear end of the machine frame for final discharge upon a mine car or the like in the usual manner.

Hydraulic devices are provided for swinging the turntable 13, for raising and lowering the parallel arms 30 and 31, and for rocking the control frame 28 to tilt the cutter bars into various cutting planes. A hydraulic pump 139 is mounted at the rear end of the main frame 12 and driven by a motor 131. The turntable swing mechanism includes a pair of hydraulic cylinders 132, 132 pivot-

ally mounted at their forward ends on brackets 133, 133 at opposite sides of the deck 12a. Each of said cylinders has a piston 134 with a piston rod 135 connected at its rear end to a sheave 136. Said sheave is mounted in a block 137 which has a flanged base 138 slidably guided along the deck 12a between a pair of guide bars 139, 139 (see Figures 11 and 15). A pair of flexible cables 140, 140 have their free ends connected to a fixed abutment, as for instance to the rear end of their respective cylinders 132. Each of said cables is trained rearwardly about the sheave 136 and thence forwardly about the periphery of the turntable 13. In the form shown herein, the cables 140 at opposite sides of the machine are integral with each other, and are anchored to the turntable at a single point at the front thereof, as by a clamp 141 (see Figure 10). By supplying hydraulic pressure to the cylinders 132, 132 in alternate directions under control of valves of the usual construction (not shown), the turntable, together with the cutter head, can be swung laterally in a relatively wide arc of approximately 180°.

25 The elevating cylinders 44, 44, effecting lifting and lowering of the parallel arms 30, 31 and the cutter head 14, are actuated hydraulically from the pump 139 under control of other valves, not shown.

30 Similarly, the control frame 28 is rocked hydraulically by a pair of cylinders 142, 142, pivotally mounted at their forward ends to the rear uprights 40 of the guide frame 37 and with their piston rods 143, 143 pivotally connected to the outer ends of pivot pins 33, 33 which connect the upper parallel arms 30, 30 to opposite sides of the control frame 28.

35 The usual power means may also be provided for operating the conveyer 20, and for propelling the machine along the mine track. In the form shown, a motor 145 is mounted on the base 10 at the rear of the turntable 13, and has driving connection with the truck wheels and the conveyer 20 respectively, through suitable gear and drive chain mechanisms which need not be described in detail, as they form no part of the present invention.

40 While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

45 I claim as my invention:

50 1. In a mining machine, a base, a cutter head including a frame having a cuttings discharge passageway extending longitudinally therethrough, a chain-carrying cutter bar mounted on said frame with its cutter chain arranged to carry the cuttings along said passageway, parallel link means for supporting said cutter head 55 in extended relation in advance of said base and for adjusting said head in a plurality of horizontal cutting planes, conveyer means on said base for carrying the cuttings rearwardly therealong, and an intermediate elevating conveyer having 55 its front end rockably connected to said cutter head independently of said parallel link means for receiving the cuttings from said passageway and conducting them to said first named conveyer in all positions of said cutter head.

60 2. In a mining machine, a wheeled base, a

turntable rotatably mounted on said base and having a centrally disposed cuttings receiving opening therein, a conveyer beneath said turntable communicating with said opening and extending rearwardly along said base, a chain-carrying cutter head disposed in extended relation in advance of said turntable and parallel link means for adjusting said cutter head to cut in a plurality of planes above and below said turntable, said cutter head having cuttings collecting means thereon associated with its cutter chain, and an intermediate elevating conveyer independent of said parallel link means having its front end rockably connected with said cutter head for receiving the cuttings therefrom and conducting them to the cuttings receiving opening in said turntable in the several positions of adjustment of said cutter head relative to said turntable.

3. In a mining machine, a base, a cutting element including a chain-carrying cutter bar and means for supporting said cutting element in advance of said base for vertical adjustment and endwise tilting movement with respect thereto, including an upright control frame mounted on said base for rocking movement on a transverse axis at a point remote from the front end of said base, a pair of parallel links extending forwardly from said control frame and connected to said cutting element, means for rocking said control frame or holding it in fixed relation with respect to said base for tilting said cutting element endwise, and means adjacent the front end of said base for moving said parallel links vertically relative to said base to adjust the cutting plane of said cutting element relative to said base.

4. In a mining machine, a base, a cutting element including a chain-carrying cutter bar and means for supporting said cutting element in advance of said base for vertical adjustment and endwise tilting movement with respect thereto, including an upright control frame mounted on said base for rocking movement on a transverse axis disposed rearwardly of the front end of said base, a pair of parallel links extending forwardly from said control frame and connected to said cutting element adjacent the front end thereof, upright guide means adjacent the rear end of said cutting element having lateral bearing engagement with said parallel links intermediate their ends, means for rocking said control frame or holding it in fixed relation with respect to said base for tilting said cutting element endwise, and means adjacent the front end of said base for moving said parallel links vertically relative to said base to adjust the cutting plane of said cutting element relative to said base.

5. In a mining machine, a base, a cutting element including a chain-carrying cutter bar, means for supporting said cutting element in advance of said base for vertical adjustment and endwise tilting movement with respect thereto, including an upright control frame mounted on said base for rocking movement on a transverse axis at a point remote from the front end of said base, a pair of parallel links extending forwardly from said control frame and connected to said cutting element, means for rocking said control frame or holding it in fixed relation with respect to said base for tilting said cutting element endwise, upright guide means on said base having lateral bearing engagement with said parallel links intermediate their ends, and means adjacent the front end of said base for moving said parallel links vertically relative to said base to

75 adjust the cutting plane of said cutting element relative to said base.

6. In a mining machine, a base, a cutting element including a chain-carrying cutter bar, 5 means for supporting said cutting element in advance of said base for vertical adjustment in a plurality of parallel cutting planes including two laterally spaced pairs of parallel links extending forward from said base, a motor rockably mounted 10 on said base between said pairs of parallel links independently of the pivotal connections of the latter, means connecting said motor and links for conjoint vertical adjustment, and flexible drive connections between said motor and 15 said cutting element for driving its cutter chain in the various positions of adjustment of said cutting element.

7. In a mining machine, a base, a cutting element including a chain-carrying cutter bar, 20 means for supporting said cutting element in advance of said base for vertical adjustment in a plurality of parallel cutting planes including a rocking frame on said base, two laterally spaced pairs of parallel links extending forward from 25 said rocking frame, a motor rockably mounted on said base independently of said rocking frame, means connecting said motor and parallel links for conjoint vertical adjustment, and flexible drive connections between said motor and 30 said cutting element for driving its cutter chain in the various positions of adjustment of said cutting element.

8. In a mining machine, a base, a turntable on 35 said base, a cutting element including a chain-carrying cutter bar, means for supporting said cutting element relative to said turntable in advance of said base for vertical adjustment in a plurality of cutting planes above and below said turntable including two laterally spaced pairs of 40 parallel links having their rear ends pivotally connected at the rear end of said turntable on vertically spaced axes, a motor rockably mounted on said turntable between said pairs of parallel links, means connecting said motor and links for conjoint vertical adjustment, and flexible drive 45 connections between said motor and said cutting element for driving its cutter chain in the various positions of adjustment of said cutting element.

9. In a mining machine, a base, a turntable on 50 said base, a cutting element including a chain-carrying cutter bar, means for supporting said cutting element relative to said turntable in advance of said base for vertical adjustment in a 55 plurality of cutting planes above and below said turntable including two laterally spaced pairs of parallel links having their rear ends pivotally connected at the rear end of said turntable on vertically spaced axes, a motor rockably mounted on said turntable between said pairs of parallel links independently of the pivotal connections of the latter, means connecting said motor and links for conjoint vertical adjustment, and flexible drive connections between said motor and said 60 cutting element for driving its cutter chain in the various positions of adjustment of said cutting element.

10. In a mining machine, a base, a turntable 65 rotatably mounted at the front end of said base, having a centrally disposed cuttings-receiving opening therein, a conveyer below and communicating with said opening and extending rearwardly along said base, a cutting element including a chain-carrying cutter bar, and cuttings-collecting means associated with said cutter bar,

an upright anchoring frame on the rear end of said turntable, two laterally spaced pairs of parallel links connecting said anchoring frame with said cutting element to permit vertical adjustment of the latter in a plurality of cutting planes above and below said turntable, and an intermediate conveyer extending longitudinally between said pairs of parallel links and connecting the cuttings-collecting means on said cutting element with said cuttings-receiving opening in said turntable in all positions of vertical adjustment of said cutting element relative to said turntable.

11. In a mining machine, a cutter head comprising a frame and a plurality of chain-carrying cutter bars mounted thereon in juxtaposed parallel planes, and drive gearing for said cutter chains disposed within the vertical limits of said cutter chains, including a sprocket shaft rotatably mounted adjacent the rear of said frame and having a drive gear thereon, drive connections to said drive gear at the rear of said frame within the vertical boundaries of said cutter chains, a sprocket on said sprocket shaft in horizontal alignment with one of said cutter bars for driving the cutter chain thereof, another of said cutter bars being disposed generally in the same horizontal plane as said drive gear, a chain-driving sprocket and sprocket shaft rotatably mounted at the rear of said last-named cutter bar, and chain drive connections between said sprocket shafts independent of the cutter chains driven thereby.

12. In a mining machine and in combination with a base, a cutting element supported for kerf-cutting movements in extended position relative to said base, said cutting element including a frame, a plurality of chain-carrying cutter bars projecting from said frame in juxtaposed parallel planes and with their cutter chains collectively presenting a substantially unitary side cutting edge adapted to cut a single kerf, the vertical boundaries of said frame being included within the vertical boundaries of said side cutting edge, power operating means for said cutter chains supported on said base, and having drive connections with the rear of said cutting element within the vertical boundaries of said side cutting edge, said last named drive connection including a bevel gear and pinion at the rear end of said frame disposed generally in the plane of one of said cutter bars, a shaft concentric with said bevel gear, having a sprocket for the cutter chain of an adjacent cutter bar and a sprocket shaft for the cutter chain of said first named cutter bar disposed forwardly of said first named sprocket shaft and chain drive connections between said sprocket shafts independent of the cutter chains driven thereby.

13. In a mining machine, and in combination with a base, a cutting element supported for kerf-cutting movements in extended position relative to said base, said cutting element including a frame, a plurality of chain-carrying cutter bars projecting from said frame in juxtaposed parallel planes and with their cutter chains collectively presenting a substantially unitary side cutting edge adapted to cut a single kerf, and driving means for said cutter chains including a shaft adjacent the rear of said frame having a sprocket engaging the chain of one of said cutter bars, a reduction drive gear in horizontal alignment with a second cutter bar, a second sprocket shaft for said second cutter bar rotatably mounted in advance of said first named

sprocket shaft, and drive connections between said sprocket shafts including a drive chain extending horizontally between adjacent cutter bars and independent of the cutter chains carried thereby.

14. In a mining machine, a cutter head comprising a frame having a cuttings discharge passageway therethrough, a plurality of cutter bars arranged in juxtaposed parallel planes, with their rear ends mounted in said passageway and having cutter chains guided thereon, drive gearing for said cutter chains including a sprocket shaft rotatably mounted adjacent the rear of said passageway and having a drive sprocket thereon for the cutter chain of one of said cutter bars, drive connections to said drive gear within the upper limits of said cutter chains and in horizontal alignment with the uppermost of said cutter bars, a chain driving sprocket and sprocket shaft for the cutter chain of said last named cutter bar, disposed forwardly of said first named drive sprocket, chain drive connections between said sprocket shafts independent of the cutter chains driven thereby, said cutter bars and chains being disposed in said passageway so as to collect the cuttings from all of said cutter chains and discharge them to the rear of said frame beneath the drive connections to the first named sprocket shaft.

15. In a mining machine and in combination with a base, a cutting element supported for kerf-cutting movements in extended position relative to said base, said cutting element including a frame having a cuttings discharge passageway therethrough, a plurality of cutter bars mounted in said passageway in juxtaposed parallel planes and projecting forwardly from said frame, cutter chains mounted on said cutter bars and collectively presenting a substantially unitary side cutting edge adapted to cut a single kerf, the upper boundaries of said frame being included within the upper boundaries of said side cutting edge, power operating means for said cutter chains supported on said base, and having drive connections with the rear of said cutting element within the upper boundaries of said side cutting edge, the last named drive connections including a bevel gear and pinion at the rear end of said frame disposed generally in the plane of the upper one of said cutter bars, a shaft concentric with said bevel gear having a sprocket for the cutter chain of an adjacent lower cutter bar, a sprocket shaft for the cutter chain of said upper cutter bar disposed forwardly of said first named sprocket shaft, chain drive connections between said sprocket shafts independent of the cutter chains driven thereby, and said cutter bars and chains being disposed in said passageway so as to collect the cuttings from all of said cutter chains and discharge them to the rear of said frame beneath said bevel gear.

16. In a mining machine and in combination with a base, a cutting element supported for kerf-cutting movements in extended position relative to said base, said cutting element including a frame having a cuttings discharge passageway therethrough, a plurality of cutter bars mounted in said passageway in juxtaposed parallel planes and projecting forwardly from said frame, cutter chains mounted on said cutter bars and collectively presenting a substantially unitary side cutting edge adapted to cut a single kerf, and driving means for said cutter chains including a shaft adjacent the rear of said frame having a sprocket engaging the chain of a lower

cutter bar, a reduction drive gear on said shaft in horizontal alignment with an upper cutter bar, a second sprocket shaft for said upper cutter bar rotatably mounted in advance of said first named sprocket shaft, drive connections between said sprocket shafts including a drive chain extending horizontally between said upper and lower cutter bars and independent of the

5 cutter chains carried thereby, said cutter bars and chains being disposed in said passageway so as to collect the cuttings from both of said cutter chains and discharge them to the rear of said frame by the action of the cutter chain of said lower cutter bar.

THOMAS E. PRAY.
